DESIGN FOR AN ADHESIVE TAPE DISPENSER

Theodore H. Krueger, Stratford, Conn., assignor to Better Packages, Inc., a corporation of New York

Application October 5, 1945, Serial No. 122,563

Term of patent 14 years

(Cl. D74—1)

To all whom it may concern:

Be it known that I, Theodore H. Krueger, a citizen of the United States, residing in Stratford, county of Fairfield, and State of Connecticut, have invented a new, original, and ornamental Design for an Adhesive Tape Dispenser, of which the following is a specification, reference being had to the accompanying drawing, forming part thereof.

Fig. 1 is a front perspective view of an adhesive tape dispenser showing my new design; and Fig. 2 is a side elevational view of the same.

I claim:

The ornamental design for an adhesive tape dispenser, substantially as shown.

THEODORE H. KRUEGER.
